No. 715,698.

Patented Dec. 9, 1902.

F. P. SALEMÉ.
KEYWAY RAIL JOINT TIE.

(Application filed Jan. 24, 1902.)

(No Model.)

Attorneys

UNITED STATES PATENT OFFICE.

FRANK PAUL SALEM, OF JUNIATA, PENNSYLVANIA.

KEYWAY RAIL-JOINT TIE.

SPECIFICATION forming part of Letters Patent No. 715,698, dated December 9, 1902.

Application filed January 24, 1902. Serial No. 91,130. (No model.)

To all whom it may concern:

Be it known that I, FRANK PAUL SALEM, a citizen of the United States, residing in the borough of Juniata, in the county of Blair and 5 State of Pennsylvania, (whose post-office is "Kipple,") have invented a new and useful Keyway Rail-Joint Tie and Common Keyway-Tie, of which the following is a specification.

My invention relates to improvements on 10 the rail-joint and fastening of rail to the tie by a keyway which is tapered; and the objects of my improvements are, first, the joining of rails on one tie; second, rails are fastened to the ties by a keyway; third, the key- 15 way protects the rail and tie, and this keyway is used for rail-joint and common tie. I attain these objects by the mechanism illustrated in the accompanying drawings, in which—

20 Figure 1 is a side elevation with a section through both rails and also shown where set-screws are located on key. Fig. 2 is an end elevation which shows that the ties are hollow and that the rail-joint tie has a rib 25 through the center of tie; also shows pointed heads on the bottom of ties. Fig. 3 is a top view of the track, which is the general arrangement of laying the ties in position; also shows how rails are connected and that the 30 keys are driven in place right and left, which are indicated by arrows; Fig. 4, a detailed view in perspective of the rail-joint tie and the blocks thereon shown for connecting rails; Fig. 5, a detailed sectional view through the 35 line 1 2. (See Fig. 2.) Fig. 6 represents two pieces of rails for connection on the rail-joint tie.

Similar letters refer to similar parts throughout the several views.

40 The part A is cast onto tie B, and blocks C are cast onto tie B, so as to hold the ends of both rails for rail-joint connection. These blocks C are only applied to tie B, which is used for rail-joint connection. The blocks 45 C are cast in position so as to allow contraction and expansion at the rail connection D. (See Fig. 6.) The triangular form cut E (see Fig. 6) is to be larger than block C, so as to allow a little clearance. Tie B and tie F 50 have pointed heads G cast on the bottom, so as to prevent the ties B and F from moving when placed in position, also that the point-

ed heads G should be located far enough apart to allow for tamping the ties B and F with stone. Ties B and F are hollow, with the 55 exception of tie B, which has a rib B through the center, so as to give it more support, for the reason that this tie B is used for rail-joint connection. When key I is driven into taper way J, it tightens the rail, and this key I to 60 have a slot K, extending parallel with the rail, also hole M (see Fig. 5) for set-screw N, which is tapped into ties B and F. This set-screw N is used in case anybody tampers with the track; also, set-screw N to have a washer O. 65 Key P is larger than key I (see Fig. 1) in case of regaging rails, by which I put key I in the place of key P, and in the place of key P, I put key I, so as to have the rails in normal condition after track is regaged. This opera- 70 tion applies only to the one side of ties B and F, which has the two taper ways J for the keys I and P. Tie F is not as large as tie B, but is made on a principle similar to tie B. (See Figs. 2 and 3.) When track is laid, ties B and F 75 are arranged in similar position, (see Fig. 3,) so as to make it secure, and when track is arranged in this position it acts as one body. The ties B and F are placed in that position throughout the distance. 80

My invention is applicable to steam, electric, and all other railway-tracks and presents a durable structure not liable to dislocation when properly adjusted and in the event of the derailment of cars prevents the track 85 from being torn up. It furthermore presents a structure which is free from obstructions to catch chains, rods, or other parts of the rigging carried by a train when the same are hanging down from the cars passing over the 90 track.

I am aware that prior to my invention tracks have been laid with wooden ties and rails fastened with bolts, nuts, nut-locks and at the rail-joint connection fish-plates used. 95 I therefore do not claim such a combination; but

What I do claim as my invention, and desire to secure by Letters Patent, is—

1. In a rail-joint, the combination with a 100 metallic tie having a keyway cast thereon and projections in said keyway, of rails having notches therein larger than and engaging said projections, of a key securing the rails in said

keyway, a slot in said key, and a bolt rigidly secured in said tie and sliding in said slot.

2. In a railway-joint, the combination with a metallic tie having a keyway cast thereon, and projections in said keyway, of rails having notches therein larger than and engaging said projections, of a key securing the rails in said keyway, a slot in said key, a bolt rigidly secured in said tie and sliding in said

slot, and pointed projections cast on the under surface of said tie.

In testimony whereof I have signed my name to this specification in the presence of two subscribing witnesses.

FRANK PAUL SALEM.
